[57] CLAIM

The ornamental design for a paper shredder or the like,
as shown.

DESCRIPTION

FIG. 1 is a front elevational view of a paper shredder or the like showing my new design;

FIG. 2 is a rear elevational view thereof;

FIG. 3 is a side elevational view taken from the left of
FIG. 1, the side opposite being a mirror image thereof;

FIG. 4 is a top plan view thereof;

FIG. 5 is a bottom plan view thereof; and

FIG. 6 is a perspective view thereof.
